GARTER CLASP

Filed April 3, 1945

FIG. 5.

INVENTOR.
Carl J. Cantello
BY

Kimmel & Crowell attys.

UNITED STATES PATENT OFFICE

2,498,154

GARTER CLASP

Carl J. Cantello, Brooklyn, N. Y.

Application April 3, 1945, Serial No. 586,346

1 Claim. (Cl. 24—264)

1
This invention relates to garter clasps.

An object of this invention is to provide an improved garter clasp which is so designed that it will not injure the threads of a stocking and at the same time will firmly hold the stocking.

Another object of this invention is to provide a clasp of this kind which has no movable parts and is so constructed that the stocking can be readily gripped or released.

A further object of this invention is to provide a garter clasp which is of simple construction so that it can be easily and quickly made.

With the foregoing objects and others which may hereinafter appear, the invention consists of the novel construction, combination and arrangement of parts as will be more specifically referred to and illustrated in the accompanying drawing wherein is shown an embodiment of the invention, but it is to be understood that changes, variations and modifications may be resorted to which fall within the scope of the invention as claimed.

In the drawings:

Figure 1 is a detail front elevation of a garter clasp constructed according to an embodiment 25 of this invention.

Figure 2 is a longitudinal section taken substantially on the line 2—2 of Figure 1.

Figure 3 is a transverse section taken substantially on the line 3—3 of Figure 1.

Figure 4 is a detail front elevation of a modified form of this invention.

Figure 5 is a transverse section taken substantially on the line 5—5 of Figure 4.

Figure 6 is a detail front elevation of another modification of this invention, and

Figure 7 is a detail front elevation of a further modification of this invention.

Referring to the drawing and first to Figures 1, 2 and 3 the numeral 10 designates generally a substantially U-shaped support which may be formed out of relatively rigid wire. The support 10 has an arcuate upper end or bight 11 and secured to and extending substantially from the bight 11 is a loop 12. The loop 12 comprises a horizontal bar 13 which is adapted to engage a supporting strap and the opposite ends of the bar 13 are bent inwardly and downwardly in convergent relation to form supporting bars 14, which may be welded or otherwise firmly secured to the bight 11. The opposite legs of the U-shaped member 10 are bent inwardly as indicated at 15 and the lower ends 16 thereof are in parallel relation. A block or lug 17 is disposed between the parallel arms 16 being of a 55

2
thickness substantially equal to the thickness of the arms 16 and having a width slightly less than the space between the arms 16, so as to provide a pair of spaces 18 within which the stocking is adapted to engage. The lower ends of the parallel arms 16 are bent inwardly as indicated at 19 and these inwardly bent ends 19 may be welded or otherwise firmly secured to the lug 17. In the present instance the opposite faces of the lug 17 are flat and these faces are covered with a rubber coating 20. The coating 20 also engages about the opposite vertical sides of the lug 17 as indicated at 21 and also engages about the upper arcuate end of the lug 17, as indicated at 22. The substantially semi-circular upper portion of the U-shaped member 10 provides a sufficiently large opening through which the material of the stocking may be extended and through which a finger may also be extended in the positioning of the stocking on the locking lug 17.

Referring now to Figures 4 and 5, there is disclosed a slightly modified form of this invention. A substantially U-shaped member 10^a is provided which is formed of a bent wire and the bight 11^a is of substantially semi-circular configuration. The opposite legs of the U-shaped member 10^a are bent inwardly as indicated at 15^a and terminate at their lower ends in parallel lower portions 16^a. A suspending loop 12^a formed of a horizontal straight bar 13^a and downwardly convergent arms 14^a is secured by welding or the like to the bight 11^a and extends upwardly therefrom. A lug 17^a is disposed between the parallel arms 16^a, the latter being bent inwardly, as indicated at 19^a, so as to thereby form a narrow space 18^a between the opposite edges of the lug 17^a and the straight arms 16^a. The lower portion of the lug 17^a is formed with a pair of cutouts or notches 23 and a rubber cap 24 is mounted about the lug 17^a and is provided at its lower open end with inwardly extending locking members 25. The rubber cap 24 may, therefore, be of the removable type so that when the cap becomes worn or unserviceable it can be replaced by a new cap.

Referring now to Figure 6, there is disclosed another modification of this invention embodying a substantially U-shaped support 10^b which has extending from the upper or bight end thereof a looped strap receiving member 12^b. The support 10^b is formed with outwardly curved opposite arms 15^b which merge at their lower ends into parallel arms 16^b. An upwardly extending lug 17^b is disposed between the arms 16^b and is

connected to the lower ends of the arms 16^b by opposite connecting members 19^b. The lug 17^b has the opposite lengthwise edges thereof spaced from the inner sides of the arms 16^b so as to thereby form spaces 18^b within which the stocking is adapted to engage. The lug 17^b, at a point adjacent the lower end thereof, is formed with a pair of oppositely extending notches 26 which provide locking or gripping means in addition to the gripping action of the lug 17^b. It will be understood that if desired a rubber cap may be applied over lug 17^b with the lower end thereof engaged in the notches 26^b similar to the construction shown in Figure 4.

Referring now to Figure 7, there is disclosed a further modification of this invention embodying a U-shaped support 10^c which is similar to the support 10^b and has extending between the parallel arm 16^c thereof a notched lug 17^c similar to the lug 17^b. The support 10^c has extending from the upper or bight end thereof an open or resilient loop, generally designated as 21. The loop 21 includes a lower bar 28 formed integral with the bight of the U-shaped member 10^c and having extending from one end thereof an upwardly extending member 29. An upper bar 30 extends at right angles from the extension 29 and overlies the bar 28 in substantially parallel relation and has extending downwardly from the opposite end thereof an extension 31 formed with an upwardly projecting hook 32. The bar 28 at a point adjacent the free end of the upper bar 30 is formed with an upwardly projecting lug 33 which provides a reduced space 34 between the upper bar 30 and the lower bar 28, so as to thereby clamp a supporting strap within the open loop. The hook or bill 32 provides a means whereby the strap will be detachably locked in the supporting loop. In other respects the construction shown in Fig. 7 is similar to that shown in Figure 6.

What I claim is:

A garter clasp comprising a substantially U-shaped support member having a bight portion and downwardly extending substantially parallel side arms, an upwardly extending blunt ended lug between and carried by the lower ends of said side arms, the side edges of said lug being disposed closely adjacent to said side arms and formed with notches therein, an upper bar forming a loop with said bight portion and a rubber cap enclosing said lug and formed with inwardly extending locking members for engaging said notches whereby said cap will provide a replaceable covering for said lug for minimizing the wear on stockings engaged over said lug and between said lug and said side arms.
